UNITED STATES PATENT OFFICE

GRAHAM B. GROSVENOR, OF CHICAGO, ILLINOIS, ASSIGNOR TO OTIS ELEVATOR COMPANY, OF JERSEY CITY, NEW JERSEY, A CORPORATION OF NEW JERSEY

ELECTRIC ELEVATOR SYSTEM

Application filed February 16, 1923. Serial No. 619,425.

My invention relates to electric elevator systems in which the elevator is brought to rest at the landings by automatic means.

In my copending application Serial No. 5 563,094, patented June 14, 1927, No. 1,632,225, I have described means for automatically fixing the speed of the elevator in proportion to the unbalanced load being lifted so that, in stopping, the effect of gravity 10 is compensated for by the kinetic energy in the moving parts. This means that the greater the unbalanced load being lifted, the faster the elevator will run. This is very important in making the actual stop from 15 low speed as it makes it possible to disconnect the elevator motor from its power supply at a fixed distance from the landing and make an accurate stop.

The object of my present invention is to 20 provide means to compensate for the effect of gravity in stopping an elevator by causing the speed of the elevator to automatically be in some predetermined proportion to the unbalanced load being lifted, the 25 means employed being applicable to various methods of elevator control hitherto in use.

I accomplish this object by the use on the hoisting motor of a series field winding which is connected in the armature circuit 30 only during such time as the elevator is being retarded, and in such a way that the flux, due to the series coils, is in the reverse sense to that produced by the separately excited field coils, these latter being always 35 supplied with current in one direction.

In order that my invention may be fully understood, it will be described in connection with the accompanying drawings, in which:—

40 Figure 1 is a wiring diagram illustrating an embodiment of my invention in a system utilizing a single voltage supply and rheostatic control.

Figure 2 is a wiring diagram of a system 45 in which a multivoltage power supply with a proper control panel is used according to my invention.

Figure 3 illustrates my invention in connection with a variable voltage current supply as set forth in my copending application

Serial No. 541,815, patented December 22, 1925, No. 1,566,399.

Referring more particularly to the drawings:—

Figure 1 is a wiring diagram for an elevator semi-automatically controlled, utilizing a common form of rheostatic control with modifications. Emergency devices and safety features have been omitted in the wiring diagrams associated with this case, 55 as these appurtenances are too well known to require description and as in the normal operation of the equipment these devices serve no purpose in connection with the present invention.

To operate the elevator motor 2, a car switch 5 is provided in the elevator car and so wired that the car switch handle 6 must be moved to either extreme position to cause the elevator to start after which car switch 70 handle 6 may be returned to neutral position at or near a landing previous to the one at which it is desired to stop. The automatic switches 7 and 8 will then automatically slow down and stop the elevator level with 75 the desired landing.

The elevator motor 2 has a constantly energized field winding 10. Suitable resistance 15 may be provided to cause the strength of the field, due to winding 10, to be of a value 80 that will give desired full speed. The field winding 10 and resistance 15 are preferably wound with conductors which will have a negligible temperature coefficient so that no variation in field strength will occur with 85 change in temperature during operation. As change in the field strength will materially change the speed, the field and other features of motor design are so designed that variation in temperature or load will not materially affect the speed.

The object in having constant speed is for the purpose of fixing the rate of retardation and the distance from the landing necessary to initiate the slow-down to provide minimum length of time for retardation, slow speed running and stopping.

Resistance 12 is protective resistance provided for field winding 10 in the event of its power supply being interrupted.

100

The operation of the elevator is described in connection with an installation where all floor heights are equal and full speed is attained when making one floor runs. This requires a constant distance for slow-down irrespective of the distance the elevator has run before initiating stopping, and for maximum transportation of freight or passengers the elevator will reach full speed midway between floors in one floor runs and slow-down will be initiated for either direction at this central point between floors. This will require but one slow-down switch 7 operating one slow-down contact for each direction of travel. In my copending application Serial No. 622,149 I have described means for automatically bringing an elevator to rest under other conditions of floor height or where the speed of the elevator is different in one floor runs from its speed in two or more floor runs.

The stopping switch 8, functioning only at the landing, requires one contact also for each direction of travel to stop the elevator.

Consider the elevator to be moved in the up direction to the next adjacent landing. Car switch handle 6 is moved to the extreme left position so that contactor 16 covers contact finger points 17, 18 and 19.

A circuit is then completed from feeder 13 through fuse 20, lines 21 and 22, up direction switch magnet coil 23, line 24, terminals F-F of traveling cable 9, line 25, contacts 26 and 27 of the terminal automatic stop switch, lines 28 and 29, contact finger 17, contactor 16, contact finger 19, line 30, terminals B-B of traveling cable 9, line 31, bottom contacts 32 and 33 of the down direction switch, lines 34 and 35, fuse 36 to feeder 14.

The up direction switch then closes contacts 37 and 38, 39 and 40, 41 and 42, and 43 and 44. Contacts 45 and 46, and 47 and 48 are opened.

The brake magnet coil is energized by a circuit from feeder 13, through line 49, contacts 38 and 37, line 50, contacts 41 and 42, line 51, brake magnet coil 3 and protective resistance 4, line 52 to feeder 14. The energizing of brake magnet coil 3 releases the brake.

The armature of the elevator motor receives power from line 13 through contacts 38 and 37, lines 53 and 54, armature winding of elevator motor 2, lines 55 and 56, contacts 39 and 40, line 57, contacts 58 and 59, lines 60 and 61, starting resistance 62 to feeder 14. Due to the fact that contacts 58 and 59 are in engagement and contacts 109 and 110 are separated, the series field winding 11 is not connected in the elevator motor armature circuit.

A by-pass resistance 67 at this time is connected across elevator motor armature leads

54 and 55 through lines 63 and 68 and contacts 64 and 65, the circuit being from lead 54, through line 53, contacts 37 and 38, line 49, line 13, line 63, contacts 64 and 65, line 66, resistance 67, line 68, line 61, line 60, contacts 59 and 58, line 57, contacts 40 and 39, line 56 to lead 55.

A circuit is also completed for the magnet coils of automatic slow-down and stopping switches 7 and 8 from feeder 13, through line 49, contacts 38 and 37, line 50, contacts 41 and 42, lines 51 and 69, fuse 70, line 71, terminals H-H of traveling cable 9, line 72, magnet coils 73 and 74 of the automatic slow-down and stopping switches 7 and 8 respectively, lines 75 and 76, terminals C-C of the traveling cable 9, lines 77, 34 and 35, fuse 36 to feeder 14.

Immediately upon the up direction switch closing, the fast speed magnet coil is energized and it closes its switch. The circuit is obtained from feeder 13 through line 49, contacts 38 and 37, line 50, contacts 41 and 42, line 51 to the right, fast speed magnet coil 78, line 79, terminals A-A of the traveling cable 9, line 80, contacts 81 and 82 of the terminal stop switch, lines 83 and 84, car switch contact finger 18, contactor 16, contact finger 19, line 30, terminals B-B of the traveling cable 9, line 31, contacts 32 and 33, lines 34 and 35, fuse 36 to feeder 14.

The fast speed switch then closes contacts 85 and 86, which completes a circuit for accelerating magnet coil 88 from feeder 13, through fuse 20, line 21, contacts 85 and 86, line 87, accelerating magnet coil 88 to feeder 14.

The accelerating magnet then closes contacts in pairs as follows:—89 and 90, 91 and 92, 93 and 94, 95 and 96 and 97 and 98 which serve to short-circuit starting resistance 62 in successive steps. Immediately upon the first section of resistance 62 being short-circuited by contacts 89 and 90, the by-pass resistance 67 is open-circuited by the contacts 64 and 65 opening.

The elevator will now run at full speed. A circuit is established through the compensating switch magnet coil 107 from feeder 13 through line 49, contacts 38 and 37, line 50, contacts 41 and 42, lines 51 and 69, fuse 70, line 71, terminals H-H of the traveling cable 9, lines 72 and 99, resistance 100, line 101, terminals E-E of the traveling cable 9, line 102, contacts 44 and 43, line 103, contacts 104 and 105, line 106, compensating switch magnet coil 107, lines 108, 84 and 35, fuse 36 to feeder 14. The last step of the accelerating magnet opens contacts 104 and 105 breaking this circuit after full acceleration. The value of the resistance 100 is such, however, that magnet 107 was not sufficiently energized to close the contacts 109 and 110 and open contacts 58 and 59, so

that series field winding 11 is still not connected in circuit.

It was shown that when contactor 16 of the car switch bridged the contact fingers 17, 18 and 19, the elevator was brought up to full speed. By centering the car switch handle 6, contactor 16 uncovers fingers 17, 18 and 19. Contact fingers 19 and 17 and 19 and 18 are still bridged by resistances which enable the direction and fast speed switches respectively to remain closed after the air gaps of the cores have been reduced by the closing of the switches. The circuit, bridging contact fingers 19 and 17 to hold in the up direction switch, extends from contact finger 19 through lines 111 and 115, contacts 116 and 117 on the automatic stopping switch, resistance 118, lines 28 and 29 to contact finger 17. For the fast speed switch, the circuit is obtained from car switch finger 19 through line 111, contacts 112 and 113 on the automatic slow-down switch, resistance 114, lines 83 and 84 to contact finger 18.

25 The elevator proceeds to a point approximately midway between landings where the magnet core of slow-down switch 7 is attracted by the stationary armature 119, which is mounted in the hatchway, opening contacts 112 and 113, thus releasing the fast speed switch by deenergizing magnet coil 78 and opening fast speed contacts 85 and 86.

35 The opening of contacts 85 and 86 deenergizes the accelerating magnet 88 which inserts resistance 62 in series with the elevator motor armature, resistance 67 in parallel with the elevator motor armature and closes contacts 104 and 105.

40 Automatic slow-down switch 7 has also closed contacts 121 and 122, which short-circuit resistance 100 in series with compensating switch magnet coil 107. The compensating switch is, therefore, closed, closing contacts 109 and 110 and opening contacts 58 and 59.

When the automatic slow-down switch is beyond the range of armature 119, contacts 121 and 122 again open but the circuit remains established through resistance 100 and sufficient current flows to keep compensating switch magnet coil 107 energized sufficiently to keep its switch closed.

45 By the opening of contacts 58 and 59 and the closing of contacts 109 and 110, the armature current of the elevator motor is caused to flow through the series field winding 11 which is so connected as to be in opposition to the shunt field winding when the motor 2 is drawing current from the line, but since, in slowing down, the elevator motor will deliver energy, the series winding 11 will increase the field strength, thereby increasing the retarding action.

55 When slow speed is reached, differential

compounding will be obtained, the demand for power by the elevator motor will be determined by its load so that with increasing loads the speed will be increased and with decreasing loads the speed will be decreased. The extremes, of course, are full load up and down. In the first case, differential compounding will cause an increase of speed while in the second case the elevator motor will deliver power since it is being driven by gravity, thereby reversing the current in the series field winding which results in cumulative compounding. The use of the series field winding here is for the purpose of slowing down and compensating for gravity at slow speeds preparatory to stopping by causing the kinetic energy of the moving parts for various loads to be inversely to the action of gravity. By properly proportioning the series winding and the shunt winding, a condition is reached that will cause the elevator to stop in the same distance, regardless of load.

When the elevator nearly reaches the landing, the magnet core of switch 8 is opposite stationary armature 120 and is attracted by it, opening contacts 116 and 117, releasing the up direction switch which interrupts current to the elevator motor armature, and applies the brake while the closing of bottom contacts on the up direction switch, connects dynamic stopping resistance 123 across the elevator motor armature leads 54 and 55, through line 127, contacts 47 and 48, resistance 123, contacts 124 and 125, and line 126.

50 Figure 2 is an adaptation of similar control as in Figure 1 for use on multi-voltage system of supply mains where four sources of supply of electrical energy are furnished connected in series to permit four equal steps of voltage; for example a battery of storage cells providing a total E. M. F. of 240 volts with three intermediate and two external supply lines. These lines may be numbered 128, 129, 130, 131, 132 and so connected as 105 to obtain 60 volts or any multiple of 60 volts with a maximum of 240 volts. The feeders are so arranged that 128 and 129 have a difference in potential of 60 volts, 128 and 130 have 120 volts, 128 and 131 have 180 volts 110 and 128 and 132 a difference in potential of 240 volts. This system is not new and is well known in the art.

55 The general arrangement of control from the elevator car is identical with that of Figure 1.

Moving the car switch handle to the extreme left position causes the elevator to run up after which starting the car switch handle 6 may be returned to neutral when the retardation and stopping will be entirely automatic.

60 As before a contactor 133 engages or bridges the contact finger points 134, 135 and 136 in the car switch 5 which completes first 115

- the up direction switch magnet coil circuit, which switch in turn completes various supplementary circuits and then the circuit for the magnet coils of the speed or accelerating switches, which in turn perform their respective duties accelerating the elevator up to full speed after which the car switch handle is returned to neutral for automatic stopping.
- 10 The shunt field winding of the elevator motor is connected permanently across the line. The series field winding is connected so as to be opposed to the shunt field winding when elevator motor 2 receives power, but is only connected in during slowing down and stopping. On starting up, contactor 133 of car switch 5 bridges contacts 134, 135 and 136 and a circuit is obtained through the up direction switch magnet coil as follows:—
- 20 from feeder 128 through fuse 137, lines 138 and 139, up direction switch magnet coil 140, line 141, terminal stop switch contacts 142 and 143, lines 144 and 145, contact finger 134, contactor 133, contact finger 136, lines 152 and 151, contacts 153 and 154, lines 155 and up 156, fuse 157, line 158 right to feeder 132.
- 25 When returning car switch handle to neutral, contact fingers 134 and 136 are still bridged through line 152, right lines 151 and 150, contacts 149 and 148, line 147, resistance 146, line 145 to contact finger 134. The resistance 146 is of such value that the up direction switch will remain in after being closed.
- 30 The up direction switch closes contacts 159 and 160, 161 and 162, 163 and 164 and 165 and 166, and opens contacts 167 and 168 and 169 and 170. The brake magnet coil is now energized from line 128 through line 171, contacts 160 and 159, line 172, contacts 164 and 163, line 173 left, brake magnet coil 3 and protective resistance 4, lines 175 and 158 to feeder 132. The brake is now lifted and the elevator will run on low speed with 60
- 35 volts available for the elevator motor armature from feeders 128 and 129 as follows:— from feeder 128 through line 171, contacts 160 and 159, line 176, armature winding of elevator motor 2, lines 179 and 180, contacts 161 and 162, line 181, resistance 177, line 178, contacts 182 and 183, lines 184 and 185, contacts 186 and 187, line 188, contacts 189 and 190 to feeder 129.
- 40 By-pass resistance 193 is also across the armature at this time from armature line 179 through lines 180, 191 and 192, resistance 193, line 194, contacts 195 and 196, lines 197 and 198 to armature line 176.
- 45 Auxiliary fast speed switch then closes as its magnet coil 199 is energized through a circuit from feeder 128 through line 171, contacts 160 and 159, line 172, contacts 164 and 163, line 174, auxiliary fast speed magnet coil 199, line 200 up, contacts 201 and 202, line 203, fuse 157, line 158 to feeder 132.

The auxiliary fast speed switch closes contacts 204 and 205, short-circuiting armature series resistance 177 and opens contacts 195 and 196, disconnecting by-pass resistance 193. Contacts 206 and 207 are closed preparatory to getting higher speed. The elevator motor is now running at low speed with 60 volts across its armature terminals and without series or by-pass resistance. Automatically, however, the elevator continues up to full speed. The successive accelerating steps are obtained by the closing of switches by magnet coils 208, 209 and 210, a circuit for these coils being obtained primarily from the car switch, and next by the closing of contacts 206 and 207 by the auxiliary fast speed switch. Magnet coils 208, 209 and 210 are electrically interlocked by means of auxiliary contacts, for sequence in operation when closing their respective switches, all receiving power from the same source.

The energization for magnet coil 208 is obtained from feeder 128 through fuse 137, line 211, magnet coil 208, line 212, contacts 207 and 206, line 213, contacts 214 and 215 of the terminal stopping switch, line 216, car switch contact finger 135, contactor 133, contact finger 136, lines 152 and 151, contacts 153 and 154, line 155 up, fuse 157, line 158 to feeder 132.

With car switch handle 6 in neutral, this circuit extends from contact 136 through lines 152 and 151, contacts 220 and 219, line 218, resistance 217 to contact finger 135. The resistance 217 is of such a value that the switches operated by magnet coils 208, 209 and 210 will remain in after being closed, but they will not pull in if open.

The closing of the switch by the energizing of magnet coil 208, raises the potential across the elevator motor armature from 60 to 120 volts as follows:—The contacts controlled by this switch operate in the following sequence. Contacts 221 and 222 close completing a circuit from feeder 129 through contacts 190 and 189, line 188, contacts 187 and 186, line 185, resistance 232, line 231, contacts 222 and 221, line 225, contacts 226 and 227, line 228, contacts 229 and 230, to feeder 130 connecting resistance 232 across 60 volts potential. Contacts 186 and 187 open, connecting resistance 233 in series with resistance 232, the line 184 instead of being connected direct to feeder 129 is now obtaining power from a point between resistances 232 and 233 connected in series across feeders 129 and 130. Contacts 223 and 224 then close short-circuiting resistance 232. The line 184 feeding the armature circuit is now direct connected to feeder 130 of the 120 volt level and resistance 233 is connected directly across the feeders 129 and 130.

Contacts 189 and 190 then open which dis-

connects resistance 233, and the armature of the elevator motor is then on the 120 volt level and the transfer resistances 232 and 233 are open-circuited.

5 Auxiliary contacts 234 and 235 and 236 and 237 on the switch controlled by magnet coil 208 are closed at this time. The closing of contacts 234 and 235 short-circuits contacts 201 and 202, controlled by the auxiliary fast speed retarding magnet coil 242, through lines 243, 156 and 203 and 442 and 200.

10 The purpose of this arrangement is to prevent auxiliary fast speed magnet coil 199 from being deenergized and thus effecting the insertion of series resistance 177 and by-pass resistance 193 in the armature circuit at other than low speed preparatory to stopping. Magnet coil 242 of the auxiliary fast speed retarding switch is connected across the armature terminals of the elevator motor 2 and so adjusted as to open contacts 201 and 202 at a voltage above 60 volts on an increasing voltage and to be of sufficient 15 strength to hold the contacts open, because of the decreased air gap of the magnet cores, at 60 volts on a decreasing voltage. Therefore, when accelerating, magnet coil 242 will not cause contacts 201 and 202 to open until after magnet coil 208 of the first 20 accelerating switch has closed contacts 234 and 235. At such time, the voltage at the armature terminals will be 120. Then when slowing down preparatory to stopping the 25 release of the switches controlled by coil 208 will open contacts 234 and 235 and since contacts 201 and 202 are open the auxiliary fast speed magnet coil 199 will be deenergized and its switch will be released to 30 connect series resistance 177 and by-pass resistance 193 into the armature circuit.

35 Contacts 236 and 237 are also closed by the energizing of the magnet coil 208 and a circuit is completed to cause the second step of acceleration by magnet coil 209 obtaining its feed from wire 213 in the same manner as coil 208 but branching off at the control panel through line 244, contacts 237 and 236, line 245, coil 209, line 211, fuse 137 40 to feeder 128. The second step of acceleration brings the elevator armature voltage up to 180 increasing this voltage 60 volts in the same manner as the switch controlled by magnet coil 208.

45 Auxiliary contacts 238 and 239, closed by the energizing of coil 209, complete the circuit for magnet coil 210 and the armature voltage is increased another 60 volts in the same manner, at which time the armature of the elevator motor will be across the two outside feeders 128 and 132 having a difference in potential of 240 volts.

50 Contacts 240 and 241 are opened by the energizing of the magnet coil 210 but do not

function at this time. The elevator will now run at full speed.

55 Consider the car switch handle 6 as having been returned to center, the slow-down will be initiated when automatic slow-down 70 switch 7 passes its respective stationary armature 119. The circuits of the magnet coils of both the automatic slow-down switch 7 and automatic stopping switch 8 are closed from feeder 128 through line 171, 75 contacts 160 and 159, line 172, contacts 164 and 163, lines 174 and 246, magnet coils 247 and 248, line 249, fuse 157, line 158 to feeder 132. The magnet core of the automatic slow-down switch 7 is attracted by the stationary armature and contacts 219 and 220 open, which causes the opening of all circuits 80 for magnet coils 208, 209 and 210 which will release their switches bringing the elevator motor armature voltage down to 60 volts. 85 These switches are mechanically interlocked or if desired may be electrically interlocked so that the releasing will be in the reverse sequence to that in which the switches were closed. 90

95 The opening of contacts 234 and 235 by coil 208 releases the auxiliary fast speed switch by deenergizing magnet coil 199 and series and by-pass resistances 177 and 193 respectively are connected in the armature 95 circuit of the elevator motor 2.

100 At the time that the slow-down switch 7 operates contacts 250 and 251 are closed by it and when the magnet coil 210 is deenergized and contacts 240 and 241 are closed a 105 circuit is obtained through compensating switch magnet coil 252 which causes the differential series field winding of elevator motor 2 to be cut in circuit, to assist during the period of slow-down and to then compensate for the action of gravity by causing the low speed to be inversely to the load imposed on the elevator motor. The circuit for compensating switch magnet coil 252 is from feeder 128 through line 171, contacts 160 110 and 159, line 172, contacts 164 and 163, lines 174, 246 and 452, contacts 251 and 250, lines 253 and 254, contacts 166 and 165, lines 255 and 256, contacts 241 and 240, line 257, magnet coil 252, lines 258 and 156, fuse 157, line 115 158 to feeder 132. The deenergizing of magnet coil 252 causes contacts 260 and 261 to close and contacts 183 and 182 to open. The closing of contacts 260 and 261 shunts the series field winding 11 across the contacts 120 182 and 183 as follows:—from contact 182 through line 262, contacts 261 and 260, line 263, series field winding 11, line 264 to contact 183. The opening of contacts 183 and 182 then interposes the series field winding in the line providing for the compounding desired. The series field winding is not provided with an adjustable shunt as it may be so designed as to give the compounding desired. 125 130

The elevator will now be running at slow speed preparatory to stopping. The potential available for the elevator armature will be 60 volts and the series field winding 11 and series resistance 177 will be in series with the armature winding. By-pass resistance 193 will be across the armature winding. Not only can an extremely low average speed be obtained but the series field winding will 10 permit higher speeds lifting the loads than that obtained when lowering the loads. The stopping of the elevator with this method of speed regulation at low speeds will be accomplished in a very short distance, lending 15 itself to extreme accuracy of stopping at floor landings by automatic means.

When the elevator platform is nearly at the landing, the core of the automatic stopping switch 8 is attracted by its stationary 20 armature 120 and contacts 148 and 149 are opened, releasing the up direction switch, thus interrupting power to the elevator motor armature, brake magnet coil and other operating circuits. Dynamic stopping resistance 25 265 is connected across the elevator motor armature through contacts 168 and 167 and contacts 266 and 267, lines 198, 172 and 176, and lines 191, 180 and 179 respectively.

20 In Figure 3, the motor generator set 268 consists of a shunt wound motor 279 driving a generator 274 obtaining power from the power feeders through main line switch 269. The separately excited field 273 of the generator 25 274 is connected across the power supply feeders 270 and 271 from feeder 270 through line 277, resistance 276, line 275, field winding 273, line 272 to feeder 271. Protective resistance 278 is connected across 40 the shunt field winding from line 275 to feeder 271, to line 272.

The separately excited field 10, and its protective resistance 12, of elevator motor 2 is connected permanently across feeders 270 45 and 271 through lines 280 and 281.

50 The elevator may be started in the up direction by moving car switch handle 6 to the extreme left hand position. After operating circuits have been established by the car switch 5, car switch handle 6 may be returned to neutral position and the elevator will continue to accelerate to a point midway between the landing from which it has started and the adjacent landing above.

55 At this midway point, the slow-down will be initiated, and the series field winding 11 will be connected in series with the elevator motor armature, being accumulative or 60 differential depending upon the flow of current through its winding. By connecting the series field winding 11 in a manner that is commonly known as differentially compounded, the elevator motor will be accumulatively compounded when delivering energy

and differentially compounded when receiving energy.

This permits series field winding 11 to assist in slowing down the elevator motor and at slow speed to increase the speed with 70 load to counteract the effect of gravity by the change in kinetic energy due to speed. When lowering the load, the speed is decreased; elevator motor 2 will deliver energy and the effect of series field winding 11 will 75 add to that of field winding 10 thereby increasing the field strength and decreasing the speed.

80 Stopping is accomplished by interrupting current to the elevator motor armature, applying a dynamic stopping resistance across the elevator motor armature and applying the brake. By holding car switch handle 6 in its extreme position, the elevator will continue to run at full speed, after it has accelerated, until the operator centers handle 6, when it will stop at the next landing beyond the first slow-down switch it encounters.

85 The circuits established by moving handle 6 over are those for the coils of the up direction and fast speed switches and they are completed by contactor 282 bridging contact finger points 283, 284 and 285. The respective paths are from contact point 285 through contactor 282 to contact point 283 and from contact point 285 through contactor 282 to contact point 284. The bridging of these contact points is done for the purpose of short-circuiting resistance 286, 100 the circuits extending from contact finger 283 through line 287, resistance 286, line 288, contacts 299 and 300, lines 301, 302 and 303 for the up direction switch magnet circuit; and for the purpose of short-circuiting resistance 307 from contact finger 284, through lines 305 and 306, resistance 307, line 308, contacts 309 and 310, lines 311, 302 and 303 to contact finger 285. The short-circuiting of resistances 286 and 307 increases the current in these circuits, permitting these magnet controlled switches to close. These switches having closed remain closed after the car switch handle has been returned to neutral, the magnet coil circuits then extending through resistances 286 and 307 and contacts 299 and 300 and contacts 309 and 310.

110 Consider now the elevator to be run one floor in the up direction and to be stopped automatically at the adjacent landing:— Car switch handle 6 is moved to the extreme left hand position and returned to neutral position immediately. Circuits from start to stop will be taken in the sequence in which 115 circuits are closed and automatically opened. Resistances 307 and 286 have been short-circuited by the bridging of the car switch finger points 283, 284 and 285 by the contactor 282. Current is increased in the cir- 120 125 130

cuit extending from feeder 270 through fuse 312, lines 313, 314 and 315, up direction switch magnet coil 316, line 317, contacts 318 and 319 of the terminal stopping switch, lines 320 and 287, contact finger point 283, contactor 282, contact finger point 285, lines 303 and 304, contacts 321 and 322, line 323, fuse 324 to feeder 271. When car switch handle 6 is returned to neutral, this circuit takes the path from line 320, through resistance 286, line 288, automatic stopping switch contacts 299 and 300, lines 301 and 302 and back on 304 as before. The up direction switch is closed by the magnet coil 316, which closes contacts 325 and 326, 327 and 328, 329 and 330 and 331 and 332 and opens contacts 333 and 334 and 335 and 336. The closing of contacts 325 and 326 permits the fast speed switch magnet coil 350 to close its switch and become self-holding in the same manner as the direction switch but as the elevator motor armature and brake magnet coil are energized, these circuits will be considered in detail first. The brake magnet coil circuit is obtained from feeder 270 through fuse 312, line 313, contacts 326 and 325, line 337, brake magnet coil 3 and protective resistance 4, line 338 to feeder 271. The brake magnet coil 3 being energized, releases the brake shoes from the brake wheel permitting the elevator motor armature to rotate. The armature of the elevator motor receives power from generator 274, the circuit being from the generator armature through line 339, contacts 330 and 329, lines 340 and 341, armature winding of elevator motor 2, lines 342, 343 and 344, contacts 331 and 332, line 345, contacts 346 and 347, line 348 and back to generator armature. The elevator motor is now at slow speed but as a circuit is established for the fast speed magnet coil, the fast speed switch closes and immediate acceleration is obtained. This circuit extends from feeder 270, through fuse 312, line 313, contacts 326 and 325, lines 337 and 349, fast speed magnet coil 350, line 351, contacts 352 and 353 of the terminal stopping switch, lines 354 and 305, contact finger 284, contactor 282, contact finger 285, lines 303 and 304, contacts 321 and 322, line 323, fuse 324 to feeder 271. Upon restoring car switch handle 6 to neutral position, a self-holding circuit for the fast speed magnet coil is still established and the fast speed switch remains closed. This circuit bridges contact fingers 285 and 284 extending from 285 through lines 303, 302 and 311, contacts 310 and 309 of the automatic slow-down switch, line 308, resistance 307, lines 306 and 305 to contact finger 284. The fast speed magnet coil 350 controls a switch which closes contacts 355 and 356 and opens contacts 357 and 358. The closing of contacts 355 and 356 short-circuits resistance 276 in series with the field winding 273 of the generator 274. The voltage of generator 274 builds up to full potential, accelerating elevator motor 2, the armature of which is supplied with power from generator 274. The opening of contacts 357 and 358 has no function at this time. The magnet coils 259 and 260 which are in parallel, are utilized to energize the automatic stopping switch 8 and the automatic slow-down switch 7. The circuit for these magnet coils is obtained from feeder 270 through fuse 312, line 313, contacts 326 and 325, lines 337 and 361, magnet coils 359 and 360, lines 362, 363 and 323, fuse 324 to feeder 271. Upon reaching a point midway between the adjacent floors constituting the run, the core of switch 7 is attracted by stationary armature 364, thereby opening contacts 309 and 310 and initiating the slow-down by deenergizing fast speed magnet coil 350 and releasing its switch thus inserting resistance 276 in the circuit of field winding 273 of the generator 274 and the voltage of generator 274 decreases with decrease of field strength. Switch 7 also closes contacts 365 and 366 completing a circuit from feeder 270 through fuse 312, line 313, contacts 326 and 325, lines 337, 361 and 367, contacts 366 and 365, line 368, contacts 327 and 328, lines 369 and 370, contacts 357 and 358 which are now closed by the release of the fast speed switch, line 371, compensating switch magnet coil 372, lines 363 and 323, fuse 324 to feeder 271. After switch 7 has passed beyond the range of armature 364, the circuit established will still remain effective by the use of resistance 373 connected across contacts 366 and 365. The resistance 373 is used for the purpose of permitting magnet coil 372 to hold in the switch controlled once it has closed, but will prevent the magnet coil 372 from operating its switch when it is open. The compensating switch closes contacts 374 and 375, which connects series field winding 11 of motor 2 across contacts 346 and 347 through lines 375 and 376 after which contacts 346 and 347 are opened, connecting the series field winding into the armature circuit of the elevator motor 2. This permits the series field winding to assist in the retardation and compensate for gravity by a change in kinetic energy. The elevator approaches low speed suitable for the load after which the elevator will be nearly to the landing at which it is desired to stop. At this time the core of switch 8 will be attracted by armature 377, thereby opening contacts 299 and 300 which will open the up direction switch magnet coil circuit releasing the switch controlled by it to interrupt power to the elevator motor armature, deenergize brake magnet coil 3 permitting the brake to apply and connect

dynamic stopping resistance 378 across armature lines 341 and 342 of the elevator motor through contacts 333 and 334, line 379 and contacts 380 and 381 so that the elevator will come to rest at the landing desired.

5 With the release of the up direction switch other operating circuits that were closed during the starting up are opened and contacts and circuits once again are as shown in the wiring diagram Figure 3.

10 The operation and circuits have been described in connection with the drawings for the up direction of travel only. It will be understood that down direction is obtained by moving car switch handle 6 to the right. 15 The circuits are all shown but not described. Magnetic slow-down and stopping switches are shown diagrammatically and may be of any suitable construction but the preferred form is the subject of my copending application Serial No. 619,426. It will be understood that there are stationary armatures for these switches at each floor, although those for but one floor are shown in the drawings, in order to simplify the diagrams. 20 It is also apparent that switches operated mechanically by cams in the hatch may be used, if desired. Other modifications of control may be made without departing from the spirit of my invention.

25 I claim:

1. An electric elevator system comprising, 30 a hoisting motor, a separately excited field winding for said motor, a series field winding for said motor, and means for connecting said series field winding in the armature circuit of said motor only during periods of retardation.

2. An electric elevator system comprising, 35 a hoisting motor, a separately excited field winding for said motor, a series field winding for said motor, and means for connecting said series field winding in the armature circuit of said motor only during periods of retardation and in such manner that its magnetizing force opposes that due to the 40 separately excited field winding when the motor is receiving energy.

3. An electric elevator system comprising, 45 a hoisting motor, a separately excited field winding for said motor, a series field winding for said motor, and means for connecting said series field winding in the armature circuit of said motor only during periods of retardation and in such manner as to assist the 50 separately excited field winding while the motor is delivering energy and to oppose the separately excited field winding while the motor is receiving energy.

60 4. An electric elevator system comprising, a hoisting motor, a separately excited field winding for said motor, a series field winding for said motor disconnected during 65 periods of acceleration and full speed running, and means for connecting said series

field winding in the armature circuit of said motor during periods of retardation.

5. An electric elevator system comprising, 70 a hoisting motor, a separately excited field winding for said motor, a series field winding for said motor disconnected during periods of acceleration and full speed running, means for initiating the retardation of said motor, and means responsive to the operation of the first named means for connecting said series field winding in the armature circuit of said motor.

6. An electric elevator system comprising, 75 a hoisting motor, a separately excited field winding for said motor, a series field winding for said motor disconnected during periods of acceleration and full speed running, and means for causing the retardation of said motor, said means including means for connecting said series field winding in the 80 armature circuit of said motor.

7. An electric elevator system comprising, 85 a hoisting motor, a separately excited field winding for said motor, a series field winding for said motor disconnected during periods of acceleration and full speed running, and means for connecting said series field winding in the armature circuit of said motor during periods of retardation and in such manner as to assist the separately excited field winding while the motor is delivering energy and to oppose the separately excited field winding while the motor is receiving energy.

8. An electric elevator system comprising, 90 a hoisting motor, a separately excited field winding for said motor, a series field winding for said motor, and means for introducing said series field winding into the armature circuit of the motor during periods of retardation in such manner that it opposes the separately excited field winding while the motor is receiving energy.

9. An electric elevator system comprising, 95 a hoisting motor, a separately excited field winding for said motor, a series field winding for said motor, and means for introducing said series field winding into the armature circuit of the motor during periods of retardation in such manner that it assists the separately excited field winding while the motor is delivering energy and opposes the separately excited field winding while the motor is receiving energy.

10. An electric elevator system comprising, 100 a hoisting motor, a separately excited field winding for said motor, a series field winding for said motor for opposing the separately excited field winding while the motor is receiving energy, regardless of the direction of rotation of the motor, and means for introducing said series field winding into the motor armature circuit during retardation.

11. An electric elevator system comprising, 105 in combination, a hoisting motor, a sep-
